UNITED STATES PATENT OFFICE.

ROBERT D. WEBB, OF MINDEN, LOUISIANA.

VALVE.

Original application filed February 2, 1918, Serial No. 215,159. Divided and this application filed July 15, 1921. Serial No. 484,891.

To all whom it may concern:

Be it known that I, ROBERT D. WEBB, a citizen of the United States, and residing at Minden, Webster Parish, State of Louisiana, have invented certain new and useful Improvements in Valves, of which the following is a specification.

The present invention relates to valves and particularly to valves adapted to control the flow of motive fluid to and from high pressure cylinders such as steam cylinders. In my copending application Serial No. 215,159, filed February 2, 1918, I describe and illustrate a cotton compress having novel means for operating the side plates thereof. One element of such means consisted in a novel valve and the present application, a division of the aforementioned application, describes and claims the valve therein illustrated. In order that the valve may be fully understood and its advantages clearly brought out it is herein-after described as an element of the compress mentioned but it will be understood that it is of universal application and is not limited in its use to cotton compresses.

In the accompanying drawings:

Figure 1 is a vertical section through the compress, the pipes for conducting the motive fluid to the cylinders operating the side plates being in dotted line;

Figure 2 is a top plan view of the upper portion of the compress showing the improved valve;

Figure 3 is a side elevation of the mechanism illustrated in Figure 2;

Figure 4 is a transverse section of the novel valve for controlling the passage of motive fluid to and from the side plate operating the cylinder;

Figure 5 is a section on line 5—5 of Figure 4 the valve plug being removed;

Figure 6 is a side view of the valve plug;

Figure 7 is a sectional view of the plug portion taken along line 7—7 of Figure 6.

The compress will not be described in detail as its construction and mode of operation are fully discussed in the patent to S. J. Webb, 828,002 issued August 7, 1906. As an understanding of its movements is an aid to a complete understanding of the operation of the valve, its general features will now be briefly stated.

55 The frame 10 of the compress supports

upon its upper end a main steam cylinder 11, in which a piston 12 is adapted to reciprocate this piston being connected by means of a rod 13 and other suitable members with the movable platen 14. Securely fastened to the heavy frame is a stationary platen 15 and between the platens 14 and 15 the bales of cotton or other bales are compressed when steam is admitted into the cylinder 11, to raise the piston 12 with its connected mechanism. In the operation of compressing the bale, however, means is provided for reducing the cross sectional area of the bale and confining the same laterally and this means comprises two side plates 16 and 17 pivoted to a stationary part of the press by pivots 18 at each side of the platen 14.

When a plantation bale is brought to the press it is placed between the widely separated platens 14 and 15 and occupies a position as shown in dotted lines in Figure 1, resting upon the inner edges of the side plates 16 and 17. Before the platen 14 is moved upward, however, to compress the bale, the side plates 16 and 17 are revolved about their pivoted lower edges to assume vertical positions thereby displacing the cotton in the plantation bale and causing it to have a smaller transverse area but a greater height. When the shape of the plantation bale has thus been altered, it is compressed between the platens 14 and 15 and then tied in the usual manner.

The mechanism for raising and lowering the side plates 16 and 17 comprises toggle links 19, 19, and 20, 20 pivoted respectively to the side plates 16 and 17 at 21, 21 and to cross pins 22, 22, rigidly held at a suitable distance from the frame 10 by means of tie rods 23, 23, and 24, 24, the links 19, 19 and 20, 20, being pivotally connected together at 25, 25. To the pins 25 are connected the lower ends of connecting rods 26 which extend upwardly and are pivoted at their upper ends to cross heads 27 slidably mounted on guides 28 secured to the frame 10. To the cross heads 27 are connected the lower ends of the piston rods 29 which extend upwardly therefrom and are secured at their upper ends to pistons 30 operating in the auxiliary steam cylinders 31. These cylinders and pistons constitute the means for actuating the side plate operating mechanism and a motive fluid is supplied to the auxiliary cylinders 31 beneath the pistons 30, the

latter are raised and draw up with them the cross pins 25 and hence rotate the side plates 16 and 17 to vertical position.

The means for supplying motive fluid to the cylinders will now be described. The upper ends of the auxiliary cylinders 31 are connected by a cross pipe or conduit 32 which communicates by means of a pipe or conduit 33 with one port of a four-way valve 34. The lower ends of cylinders 31 are connected together by means of a pipe or conduit 35 having a short branch 36 communicating with a second port of the four-way valve 34. The other ports of the valve are connected respectively to a source of steam supply by means of a pipe 37, and to the outside air or a suitable condenser, by means of a pipe or conduit 38. The valve is shown in detail in Figures 4 to 7 inclusive, in which the valve body 39 is shown as having two pairs of opposed openings so that it closely resembles in exterior appearance the usual, common, four-way pipe connection.

25 A central cylindrical recess 40, open at one end, extends nearly through the body and four rectangular ports 41, 42, 43 and 44 bring this recess 40 into communication with the four openings in the casing, the ports 42, 43 and 44 being all arranged on one side of a central line through the valve casing, as line 5—5 of Figure 4. Mounted for rotation within the cylindrical recess 40 is a cylindrical plug 45 having the recesses or 35 passages 46 and 47 leaving a comparatively large bearing surface 48 and a comparatively small bearing surface 49 on opposite sides thereof adapted to seat against the wall of the valve body in the usual manner. This 40 plug 45 is adapted to occupy one of three positions in the operation of the compress. In Figure 4 I have indicated by means of full and dotted lines these positions. When the valve has been turned to its full line 45 position as shown in this figure, no two of the ports communicate with each other; when it is turned to the dotted position 50 the ports 41 and 42 are brought into communication and also the ports 43 and 44. When 50 it is turned to the dotted line position 51, the ports 42 and 43 alone communicate, the ports 41 and 44 being closed.

Referring to Figures 2 and 3 of the drawing, the pipe 37 is so connected to the valve body 39 that the port 41 is an inlet port for the steam coming from the boiler. The pipe 33 leading to the tops of the cylinders is connected to communicate with the port 43, the pipes 35 communicate with the port 42, and the pipe 38 communicates with the port 44. Thus the ports 41 and 44 are inlet and exhaust ports respectively, while the ports 42 and 43 may be either inlet or exhaust ports, depending upon the position of the 65 valve.

In the operation of the compress, when it is desired to raise the side plates the plug 45 is turned by means of a handle 52 to occupy the dotted line position 50 connecting the ports 41 and 42, and also 43 and 44 respectively, and allowing steam to pass through the valve from the supply pipe 37 into the pipes 35 and under the pistons 30, which are raised thereby, the steam above the pistons being simultaneously exhausted through the pipes 32, 33 and ports 43 and 44 and pipe 38.

When it is desired to lower the side plates the plug 45 is turned until it occupies the dotted line position 51 of Figure 4, in which case the ports 42 and 43 only are brought into communication, thereby connecting the tops of the cylinders with the lower ends and cutting off the inlet and exhaust. When in this position the pressures on the upper and lower sides of the pistons 30 are equalized, the steam passing from beneath the piston through ports 42 and 43 to top of pistons, and the pistons are free to drop due to their own weight and the weight of the attached mechanism, thereby lowering the side plates. The bale of cotton is then removed and a fresh plantation bale placed in the machine and the cycle of operations repeated, it being understood of course that the movable main platen 14 performs the actual compressing of the cotton during the time when the side plates are in their vertical position.

By connecting the bottom and top of the cylinder in this manner to lower the pistons and side plates, a considerable saving of steam is effected inasmuch as the pistons fall of their own weight and it is not necessary to introduce steam pressure into the cylinders above them to drive them down as was the case heretofore. The speed of the machine is also increased since if it were necessary to exhaust the steam each time from underneath the pistons directly into the open air, these pistons would not begin to fall so quickly and thereby delay the fall of the side plates.

Heretofore in operating compresses of this type it has been found necessary to introduce live steam into the cylinders above the pistons in order to drive them down quickly, thus using a large amount of steam for merely returning the side plates to horizontal position, and when the live steam pressure on the top of the pistons became greater than that beneath the same, the operation became more or less dangerous, and was likely to cause a bad break and to endanger the operatives. With my improved valve and combination of pipe connections described, it is impossible to introduce live steam above the pistons and the pressure on the tops of the pistons can never be greater than that underneath, thus making the op-

eration of the machine safe and more economical.

Due to the form of valve used, leakage of steam from the supply pipe to the cylinders is prevented as the ports 42, 43 and 44 are located at one side of an axial plane and the fluid pressure acting in the recess 47 against the plug forces the same against the inner wall of the body at all times and, as it moves from one position to the other, causes it to firmly seat and thus prevent leakage between the plug and body being thus self-packing. This is important also in a machine of this type because it is very undesirable that any steam should leak to the top of the piston when the valve is closed thus allowing the pistons to come down unexpectedly.

With this type of valve also the exhaust outlet from the top of the cylinders leading to the outer air may be reduced in area or throttled (as shown in Figure 4) and the live steam inlet pipes and ports leading from the boiler and to the bottom of cylinder enlarged as shown so that the pistons move simultaneously when steam is admitted under them and do not rise one after the other, as is often the case when steam is admitted slowly, unless complicated and expensive devices are employed. The use of this valve renders unnecessary these auxiliary equalizing devices thus rendering the compress simpler and more efficient since these mechanisms are hard to adjust and are easily disarranged.

Having thus described the invention what I claim as new and desire to secure by Letters Patent is:

1. In a valve, a hollow valve body having four ports only therein, a single plug in said body and constituting a rotatable partition, said plug being adapted to prevent communication between any of said ports when in one position, to bring two adjacent ports only into communication when turned to a second position, and to bring said ports into communication in pairs when turned to a third position.

2. In a valve, a hollow valve body having two inlet and two outlet ports therein, and a single plug in said body adapted to prevent communication between any of said ports when in one position, to bring one inlet and one outlet port only into communication when in a second position, and to bring each inlet port into communication with an outlet port when in a third position.

3. In a valve, a hollow valve body having two inlet and two outlet ports therein, and a plug therein having a wedge shaped cross section, said plug constituting a rotatable partition and being adapted to prevent communication between any of said ports when in one position, to bring one inlet and one outlet port only into communication when in a second position, and to bring each inlet port into communication with an outlet port when in a third position.

4. In a valve, a body having two inlet and two outlet ports therein, three of said ports being to one side of a plane through the axis of the valve casing, and a plug therein of substantially wedge shaped cross section and having relatively large and relatively small opposed surfaces adapted to bear against the wall of said casing, said valve being adapted to prevent communication between any of said ports when in one position, to bring one inlet and one outlet port only into communication when in a second position, and to bring each inlet port into communication with an outlet port when in a third position.

5. In a valve, a hollow valve body having four spaced ports therein, and a rotatable plug of substantially wedge shaped cross section in said body and having relatively large and relatively small opposed surfaces adapted to bear against the wall of said body, three of the spaces between said ports being substantially equal to the small end of said plug, and the remaining space being substantially equal to the large end of said plug.

6. A valve as claimed in claim 5, wherein one of said ports, constituting an outlet port, is restricted in area relatively to the other ports, as and for the purpose described.

7. In a valve, a hollow valve body having four ports therein, and a rotatable plug in said body adapted to prevent communication between any of said ports when in one position, to bring two adjacent ports only into communication when turned to a second position, and to bring said ports into communication in pairs when turned to a third position, one of said ports constituting an outlet port and being restricted in area relatively to the other ports.

In testimony whereof I hereunto affix my signature.

ROBERT D. WEBB.
